(57) CLAIM

The ornamental design for a macramé bracelet with a lock, as shown and described.

DESCRIPTION

FIG. 1 is a top and front perspective view of a macramé bracelet with a lock showing my new design; and,
FIG. 2 is a rear perspective view thereof.

The broken lines shown in the drawings represent portions of the macramé bracelet with a lock and form no part of the claimed design.

1 Claim, 2 Drawing Sheets
